[57] ABSTRACT

Method of and apparatus for deliquefying and compacting refuse. The apparatus is provided with a hydraulically operated vertically reciprocating ram and a vertically movable compaction chamber hydraulically operated independently of the ram. The bottom edge of the compaction chamber is scalloped to form, in conjunction with the base of the apparatus, openings through which liquids present in the refuse may be expelled during the compaction process. After refuse compaction, the chamber is raised above the base to enable a disposal bag to be placed over the lower portion of the chamber. The refuse is then ejected into the bag.

5 Claims, 1 Drawing Figure

REFUSE COMPACTOR AND METHOD

BACKGROUND OF THE INVENTION

This invention relates to refuse compactors and more particularly to a vertical compactor for deliquefying, compacting and packaging refuse such as trash, rubbish and garbage for disposal. The volumetric reduction of refuse by compression or compaction is well-known. Generally, compactors in common use in households compress refuse into a bag or carton located within the compaction chamber. Compaction pressures of 15 to 40 psi are typical for such household compactors. Higher pressures, for example, in the range of 100 to 150 psi are not feasible in such devices because of the possibility of rupturing or puncturing the bottom or walls of the bag. U.S. Pat. No. 3,528,366 shows an apparatus for compacting refuse wherein the disposal bag walls are external to the compaction chamber. The problem of rupturing or puncturing the disposal bag still exists in the apparatus described in this patent because during the compaction cycle the bottom portion of the bag is subjected to high compaction pressures.

In U.S. Pat. No. 2,817,290, a vertically movable ram compresses garbage upwardly into a housing. The ram comprises a flat plate having a plurality of apertures therethrough for the purpose of draining liquids expressed from the refuse. A disadvantage of this arrangement is that if waste matter becomes impacted in one or more of the apertures, liquids will not effectively drain from the compression housing.

SUMMARY OF THE INVENTION

The present invention is a novel vertical refuse compactor enabling the use of relatively high compaction face pressures such as, for example, 100 to 150 psi. Refuse is loaded into the top of an upright open-ended chamber movable in the vertical direction. The compaction chamber rests on a solid base during the compaction cycle and the bottom edge of the chamber is scalloped. A reciprocating hydraulically operated ram positioned above and in axial alignment with the chamber compacts the refuse and simultaneously expresses waste liquids in the refuse through the openings formed by the scalloped edge of the tube and the top surface of the base upon which the chamber rests. As a result of the high compaction pressure, the refuse is firmly compacted in the lower portion of the chamber and is frictionally retained therein without support by the base. After compaction the chamber is raised to a position above the base and a disposal bag is then positioned over the lower portion of the chamber. Next, the chamber is lowered to a position adjacent the base and the ram positioned against the top surface of the refuse. As the chamber is raised the compacted refuse is ejected into the disposal bag which is removed from the compactor for disposal.

According to the present invention the bag is not subjected to high compaction pressures during any part of the compaction cycle, thereby eliminating the possibility of rupturing or puncturing the bag. The feature of the scalloped bottom edge of the compaction chamber has the advantage of overcoming impaction of waste matter in the openings through which liquids are expressed from the refuse. It should be noted in connection with this feature that when the chamber is raised above the base the continuity of the liquid openings is interrupted.

The term "scalloped" as used to describe the bottom edge of the chamber in the specification and claims herein is to be understood to include many configurations of an irregular bottom edge of the chamber the purpose of which is to provide drain openings for liquid expelled from the refuse. Such configurations may have, for example, arcuate, square, rectangular, or saw-tooth shapes, or combinations thereof.

OBJECTS OF THE INVENTION

An object of the invention is to enable the use of high compaction pressures in a refuse compactor in a manner which precludes damage to the disposal bag or container in which the refuse is discarded.

Another object of the invention is to provide a compactor for deliquefying refuse in which the waste liquid drain openings will not become impacted with waste matter.

Other objects, advantages and novel features of the invention will appear from a reading of the following detailed description of the invention when considered in conjunction with the accompanying drawings.

DETAILED DESCRIPTION OF THE PREFERRED EMBODIMENTS

The single FIGURE of the drawing illustrates a side view, partly in cross-section, of a refuse compactor incorporating the principles of the present invention. The apparatus comprises a hollow cylindrical compaction chamber 11 resting upon a solid stationary base having a cup-like cavity 13 centrally located in its top surface. The cavity 13 has a minimum diameter appreciably greater than the maximum diameter of the chamber 11 so as to form an annular groove 14 between the base 12 and the chamber 11. The compaction chamber 11 is an upright metal tube open at both ends and, as indicated, preferably cylindrically-shaped although it may be in other forms such as a square. The bottom edge of the chamber 11 is scalloped, that is, provided with a plurality of spaced irregularities such that when the chamber 11 rests upon the base 12 a plurality of openings 15 are formed, the purpose of which will be subsequently described herein. The irregularities at the bottom edge of chamber 11 as shown in the drawing, are in the form of evenly-spaced arcuate indentations although, as hereinbefore mentioned, may be of other than arcuate shape and need not be evenly spaced.

Located above and in substantial axial alignment with the chamber is a cylindrically-shaped ram 16 which is capable of being raised and lowered so as to be vertically slidable within the chamber 11. A pair of radially extending horizontal arms 17 are fixedly attached to the upper portion of the ram 16 in oppositely disposed locations. The ram 16 is supported in position above the chamber 11 and vertically movable by two upright hydraulic pistons 18 secured to the outer extremities of the arms 17 and actuated by hydraulic cylinders 19. In similar manner, the compaction chamber 11 is vertically movable by a pair of upright hydraulic cylinders 20 and pistons 21 secured to an intermediate portion of arms 22 which are fixedly but oppositely attached to the upper portion of the chamber 11 and extend horizontally therefrom.

A frame, shown generally at 23, includes a pair of vertical guideways 24 each of which is formed of an elongated rectangular metal tube centrally slotted to receive the arms 17 and 22. Guide bearings 25 and 26,

rotatably mounted on the arms 17 and 22 respectively, are slidably disposed within the interior of the guideways 24 and bear on the inner walls thereof so as to maintain substantial axial alignment between the ram 16 and the chamber 11. A drain pipe 27 for carrying away waste liquids is connected to the base 12 and communicates with the annular groove 14 formed between the base and chamber 11 when the chamber is resting upon the base. If desired, a plurality of drains may communicate with the groove 14 to provide more rapid drainage. To avoid refuse adhering to the interior of the chamber and the exterior surface of the ram after the compacted refuse is expelled it is preferred that both of these surfaces be smooth.

The operation of the refuse compactor, in accordance with the present invention, commences with the components positioned as shown in the drawing. Hydraulic cylinders 20 are actuated by control equipment (not shown) to drive the pistons 21 downwardly so as to force the chamber 11 firmly against the base. Refuse is then loaded into the chamber 11 at its upper open end 28. When the chamber is fully loaded hydraulic cylinders 19 are actuated to drive the ram 16 downwardly thus compacting the refuse against the base 12 at a face pressure of 100-150 psi. As the ram 16 is driven downwardly any liquids entrained in the refuse will be expressed out of the chamber through the openings 15 and into the annular groove 14. Waste liquids collected in the groove are then drained out through drain pipe 27. A water source may be used to rinse the groove so as to dilute the waste liquids and promote drainage thereof. After sufficiently compacting the refuse the ram is hydraulically raised and the chamber may be charged with another load of refuse and compacted as before. The compaction cycle may be repeated until the chamber 11 is filled with compacted refuse to a predetermined depth. With the ram 16 in its retracted or uppermost position, hydraulic cylinders 21 are actuated to raise the chamber 11 to a position several inches above the base. Because of the high compaction pressure the refuse will remain impacted in the lower portion of the chamber. After the chamber has been raised a disposal bag or other appropriate container is then manually inserted between the base 12 and the chamber 11. If a bag is used it is slid upwardly to a position adjacent the arm 22 so as to enclose the lower portion of the chamber therewithin. The chamber, now with the bag in place around its lower portion is again lowered to the base by actuating hydraulic cylinder 21. Next, the ram 16 is lowered against the upper surface of the refuse and the chamber 11 raised thereby ejecting the slug of impacted refuse into the bag. After raising the ram, the bag is then removed from the compactor and all components are returned to their positions as shown in the drawing for commencement of another compaction cycle.

Obviously, many modifications and variations of the present invention are possible in light of the above teachings without departing from the spirit and scope of the appended claims.

What is claimed is:

1. A refuse compactor, comprising:

a base;
an upright hollow chamber having top and bottom open ends devoid of cover plates and adapted to rest on the top surface of said base, the bottom edge of said chamber being scalloped;

a ram positioned above said chamber in axial alignment therewith;

hydraulic means for reciprocating said ram relative to said chamber whereby refuse loaded into said chamber is compacted between said ram and said base and whereby waste liquids present in the refuse are expelled through the openings formed between the bottom scalloped edge of said chamber and the top surface of said base; and

second hydraulic means for vertically moving said chamber upwardly or downwardly relative to said base and said ram.

2. In a refuse compactor having an upright open-ended hollow chamber adapted to rest on a base and a vertically slideable ram positioned above said chamber and in axial alignment therewith, the method of compacting the refuse comprising:

loading said chamber with refuse;
compacting the refuse within said chamber with said ram; then

raising said chamber with the refuse compacted therein to a position above said base; then
placing a disposal container around said refuse compacted chamber between said base and the bottom end of said chamber while said chamber is raised; then

lowering said refuse compacted chamber with said disposal container therearound until said container contacts said base;

moving said ram downwardly to a position in contact with the top surface of the compacted refuse; and then.

moving said chamber upwardly while said ram is in the downward position thereby ejecting the refuse into said container for disposal.

3. The method of compacting refuse according to claim 2 including applying a pressure in the approximate range of 100 to 150 psi to said refuse during said compacting operation.

4. In a refuse compactor having an upright open-ended hollow chamber adapted to rest on a base and a vertically slideable ram positioned above said chamber and in axial alignment therewith, the method of compacting the refuse comprising:

loading said chamber with refuse;
compacting the refuse within said chamber with said ram;

raising said chamber with the refuse compacted therein to a position above said base; subsequently placing a disposal container around said chamber between said base and the bottom end of said refuse compacted chamber while said chamber is raised; then

lowering said refuse compacted chamber with the container therearound to a position adjacent to said base;

moving said ram downwardly to a position in contact with the top surface of the compacted refuse;

moving said chamber upwardly while said ram is in the downward position thereby ejecting the refuse into said container;

moving said ram upwardly from the top surface of the refuse; and

removing the container from the chamber with the refuse within the container.

5. The method of compacting refuse according to claim 4 including applying a pressure in the approximate range of 100 to 150 psi to said refuse during said compacting operation.
